UNITED STATES PATENT OFFICE.

CHARLES K. STINSON, OF NEW YORK, N. Y., ASSIGNOR TO THE AMERICAN CARPET LINING COMPANY, OF SAME PLACE.

MACHINE FOR MAKING CARPET-LINING.

SPECIFICATION forming part of Letters Patent No. 244,496, dated July 19, 1881.

Application filed June 10, 1881. (No model.)

To all whom it may concern:

Be it known that I, CHARLES K. STINSON, a citizen of the United States, residing at New York, in the county and State of New York, 5 have invented certain new and useful Improvements in Machines for Making Carpet-Lining, of which the following is a specification.

My invention relates mainly to a machine adapted to the manufacture of a carpet-lining which is composed of a corrugated sheet of paper secured at uniform intervals to a plain continuous sheet of paper, the grooves or corrugations being filled with cotton or other suitable material, and the edges finished bylapping the lower paper over and upon the upper to make a closed edge.

In the accompanying drawings, which serve to illustrate my invention, Figure 1 is a view, in side elevation, of my improved machine, and 20 Fig. 2 is a sectional view of the lining which my machine is designed to manufacture.

A is the main body of the frame of the machine, which is shown as constructed of piping or tubing of requisite size, jointed in any well-known way, and within which is mounted in suitable bearings the feeding, carding, and cutting mechanism.

B B' are rolls of paper hung in bearings a a'. The two together form the envelope or covering for the lap, the paper from the roll B', after passing through the paste-rolls, taking the strips or sections of the lap as they fall from the cutting-roll and bearing them onto the heated corrugating-rollers, where it meets the paper from roll B as it passes out from between said rolls, and thence the whole is carried on, beneath the lower corrugated roll, to the drying-cylinder.

A' is that portion of the frame which I designate as the "scratcher-frame." Within this is arranged the mechanism for forming the cotton in a continuous lap or bat. From the lap-racks C C' and strainers the cotton is delivered to the scratchers E E' by feed-rollers F F', and thence onward to the revolving screens G G', from which point it is carried by suitable ways or aprons in a continuous lap to the cutting and compressing roll. The scratchers E E', and the mechanism acting in conjunction 45 with each, are arranged at different elevations

within the frame, and each scratcher works independently, so that a double lap is thrown, each lap as it comes from its respective scratcher being one-half the thickness, and the two distinct laps unite after leaving the screen G G', and a lap of the desired thickness is delivered to the cutting and compressing roll. 55 By this arrangement I am enabled to work the cotton much faster than is possible where one lap only is thrown, as is the case where but one scratcher is used.

The paper from the roll B', which serves for the under side, is about two inches wider than the paper on roll B, to enable it to be lapped or folded over the edge of the corrugated surface, as will be more fully set forth hereinafter. 65 This paper is passed between the paste-rolls b, which are fed by "doctor-rolls" b' suitably arranged within a paste-vessel, c, in the ordinary manner, and on and over the endless apron H. 70 The apron H passes around suitable bearing-rolls, d d', arranged within the main frame of the machine, and is caused to press closely up to the cutting-roll, so that the paper may readily take the strips or sections of the lap as they 75 are cut off.

One or more cutting-blades, e, are set in or otherwise secured to the periphery of the roll I. Beneath this roll I is hung a bearing-roll, J, its surface covered with any material suitable for the blade to cut on. As the lap passes between these rolls it is cut crosswise into strips or sections, of a width adapted to the corrugations in the paper which is designed to inclose such sections. These strips as they 85 come from the cutting-roll are caused to fall upon the paper at uniform distances apart, and this spacing I accomplish by a positive independent rotary motion of the paper-carrying mechanism, the adjustment being such as 90 to cause the paper to travel with a velocity exceeding that of the lap, and the spaces between the lap-strips may be increased or diminished by accelerating or retarding the speed of the paper relatively to that of the cutting-roll. After receiving the lap-strips the paper passes beneath the corrugated rollers K, which are delivering the paper from roll B in a corrugated form, and the whole is submitted to pressure beneath said roll, the upper paper inclos- 95 100

ing the laps and being secured to the under paper between each section, presenting the appearance shown in Fig. 2. From thence the finished lining is passed over and between 5 heated rolls and pipes, as will now be described.

The corrugating-rolls K K' are hollow steam-heated drums arranged to rotate in bearings f, the lower one, K', pressing hard against the 10 cylinder L and endless apron H. The drying-cylinder L is constructed of a continuous coil of pipe, and provided with suitable means for admitting steam at one end of the coil and exhausting it at the other.

15 g g are the spokes or arms of the cylinder, of similar piping, and h is a piping-shaft having its bearing in the cast-iron box i, which is chamfered out and packed at each end. Steam is admitted to the cylinder at the valve 20 j, passes through the vertical pipe k, into the hollow bearing i and shaft h, and thence through the arms g into the cylindrical coil, and on and out by a similar arrangement on the other or opposite side.

25 M is a piping-shell, which is secured to the frame of the machine, and which incloses the cylinder L. It is placed about one inch therefrom, affording sufficient room for the lining to pass between it and the cylinder. Steam 30 is admitted through valves suitably arranged therewith. After leaving the corrugating-roll K the lining passes over the cylinder L to the folder or binder m arranged on the shell M, which is adapted to turn the edge of the lower 35 paper over and upon the upper one, and thence on and between the solid roll N, which presses the edges of the fabric closely together. It then passes between the cylinder and the hollow steam-drum O, provided with a corrugated 40 surface to fit the corrugations in the lining, and from thence encircles the cylinder L until it reaches the roll n, around which it is passed, and thence carried in a reverse direction around the outside shell, M, and over the roll o, through 45 the marking-rolls p p, to the folder or receiving-box q.

By constructing the drying-cylinder with an outside steam-heated shell I am able to get double the amount of drying-surface without 50 much increase of space.

The roll O, as stated, is a hollow steam-drum geared to the cylinder, its surface being corrugated, and this likewise greatly facilitates the drying of the upper or corrugated surface 55 of the fabric.

In my present construction I have shown the frame of the machine as all constructed of piping, which may vary in size from one and a half to two inches. The arches l l, within which 60 the roll o and marking-rolls p p are mounted, may likewise be made of similar piping.

Beneath the scratcher-frame is arranged a blower, s, in the usual manner, to facilitate the passage of the cotton flock by creating a draft 65 from underneath it.

What I claim as new, and desire to secure by Letters Patent, is—

1. The combination, in a carpet-lining machine, of double scratchers and screens, conjointly with the usual lap-forming mechanism 70 so arranged as to work independently of each other, whereby a lap of one-half the desired thickness is thrown to the cutting-roller from each screen, substantially as herein shown and described.

2. The combination, in a carpet-lining machine, of a cutting and compressing roll to take the continuous lap as it comes from the scratchers and cut it into sections, pasting-rolls to apply paste to the lower paper, an endless 80 apron to carry said paper in proper conjunction with the cutting-roll to receive the sections of the lap as they are cut off, and corrugating and compressing rolls to corrugate the upper paper and compress the whole together, substantially as set forth.

3. The mechanism for securing the sectional laps on the continuous sheet of paper at uniform distances apart, which comprises a cutting and compressing roll, an endless apron, and 90 corrugating and compressing rolls, the said parts being so arranged relatively to each other that the speed of the apron is greater than that of the cutting-roll, as and for the purpose set forth.

4. The combination, with the cutting and compressing roll and endless apron running at a greater speed than said cutting-roll, of steam-heated corrugating-rollers adapted to corrugate the paper for the upper covering 100 laps, and secure it, at points between the sectional laps, to the lower paper, substantially as herein shown and described.

5. In a carpet-lining machine, the combination, with mechanism for forming the lining, 105 of a drying-cylinder constructed of a continuous coil of piping having suitable supply-pipes for the admission of steam, and provided with an outer shell of piping, whereby a double heating-surface is provided, as and for the purpose described.

6. The combination, with the drying-cylinder, of a folder or binder, m, pressure-roll N, corrugated steam-drum O, and roll n, all arranged and operating substantially as described. 115

7. The combination, in a carpet-lining machine, with mechanism for forming the lap, of a cutting and compressing roll, paste-rolls, corrugating and compressing rolls, binder, drying-cylinder, with bearing-rolls arranged to work in connection therewith, marking-rolls, and folder-box, all constructed to operate in the manner herein shown and described.

CHARLES K. STINSON.
